SALT ATTACHMENT FOR ICING MACHINES

Harold O. McLain, Highland Park, Ill.

Application August 24, 1950, Serial No. 181,238

4 Claims. (Cl. 62—1)

1

The present invention relates generally to ice servicing machines for icing or servicing refrigerator cars, but more particularly to a salt supplying attachment or trailer for an icing or ice servicing machine so as to furnish the proper or regulated amount of salt with the crushed ice when the same is required.

One of the primary objects of the present invention is to provide a novel and improved construction of a salt supplying device or salt supplying attachment for refrigerator car icing machine which is not only simple in construction, but which may be readily attached to or connected in such a manner as to be actuated by the icing machine and controlled therefrom.

A further object of the invention is to provide a novel and improved salt supply attachment for an icing machine having means associated therewith and controlled from the icing machine for supplying a predetermined amount of salt with the crushed ice of the icing machine.

These and other objects are accomplished by providing a construction and an arrangement of the various parts in the manner hereinafter described and particularly pointed out in the appended claims.

Referring to the drawings:

Fig. 1 is a top plan view of a fragmentary portion of a refrigerator car ice servicing machine showing the manner in which my improved salt supply trailer attachment may be connected thereto;

Fig. 2 is an enlarged cross sectional view taken on the lines 2—2 in Fig. 1;

Fig. 3 is a side elevational view of the device shown in Fig. 1;

Fig. 4 is a rear elevational view of the same; and

Fig. 5 is a side elevational view of one of the motors and the means for driving the salt conveyor.

In illustrating one adaptation of my invention, I have shown the same in connection with a self-propelled refrigerator car icing machine of the construction disclosed in my co-pending application, Serial No. 53,105, filed October 6, 1948, now Patent No. 2,587,872, March 4, 1952, on Icing Machine. A fragmentary portion of this icing machine is shown in Figs. 1 and 3 of the drawings and comprises briefly a longitudinally extending main frame 10. The opposite ends of the main frame 10 are supported on suitable front and rear sets of transversely extending truck frames, generally indicated by the reference character 11 (only one of which is shown in the drawings).

2

Each of these truck frames comprises transverse spaced apart channel members 12, vertical spaced apart channel members 13 and horizontally extending and laterally spaced apart tracks 16. Mounted on the main frame is an ice crusher and breaker mechanism, generally indicated by the reference character 17. A horizontally and transversely extending conveyor (not shown) is mounted between the channel members 12 for conveying the crushed ice from the ice crusher and breaker mechanism 17 laterally in either direction to oppositely disposed ice chutes, generally indicated by the reference character 18. These chutes are vertically adjustable and are for the purpose of discharging the crushed ice laterally into the hoppers or bunkers located in the opposite ends of the refrigerator cars. The icing machine is provided with an operator's station or platform, generally indicated by the reference character 18', from where the control and operation of the unit or the operating elements thereof, as well as the operation of the salt supplying mechanism may be controlled.

My improved salt supplying attachment is adapted to be used in connection with an icing machine of the type described and for a more detailed description of the same, reference to the previously mentioned co-pending application may be had. The salt supplying attachment, of course, is especially adapted for this particular machine and controls for the salt supplying attachment are located within easy reach of the operator on the icing machine. The salt attachment may be used in connection with other forms or types of icing machines with very little, if any, modification.

My salt supplying attachment in this instance comprises a trailer-like wheeled frame and includes two longitudinally extending and spaced apart channel members 19 which have their opposite ends connected together by transverse channel members 20. Depending from the opposite ends of each of the channel members 20 and secured to the opposite channel members 19 are vertically depending pairs of channel members 21. Positioned below each of the channel members 20 and having their opposite ends secured to the opposite vertical channel members 21, are supplemental channel members 22. Secured to the lower ends of each of the vertically spaced pairs of channel members 21 are horizontally positioned spaced apart channel members 23 between which are horizontally spaced grooved truck wheels 24 which are adapted to engage and ride upon the opposite tracks 16. The wheeled

truck frames are reinforced or braced to the transverse frame members 20 by suitable angle members 25. The salt trailer is attached to the self-propelled icing machine 17 by two laterally spaced lowered draft bars or members 26 and a single central upper draft member 25'.

Located in the longitudinal center of the trailer frame and between the spaced apart and transversely extending channel members 20 is a salt hopper, generally indicated by the reference character 26'. The hopper 26' is substantially square in cross section and includes four vertically extending opposite side and end walls 27, the vertical edges of which are connected to vertically extending angles 28 to form the corners and reinforce the side and end walls. The lower portion of the hopper 26' is divided in the longitudinal center thereof by oppositely inclined sloping surfaces or bottom sections 29 with their upper or converging portions terminating in a division or apex 30 located at a slight elevation above the lower portion of the hopper. The other portions of the bottom of the hopper, as shown at 31, converge inwardly to form funnel-like constructions terminating in circular salt discharge openings 32 on each side of the division wall or apex 30. Connected to these funnel-like portions of the hopper 26' in alignment with each of the discharge openings 32 therein, is a circular conduit or pipe 33 which communicates with and is adapted to discharge the salt into the receiving or inner ends of each of two conveyor troughs, generally indicated by the reference character 34. These salt conveyor troughs 34 are identical in construction and are disposed on the opposite sides of the salt attachment and diverge outwardly and angularly so as to have their delivery ends positioned over the inner portions of each of the outwardly projecting crushed ice chutes 18 so as to discharge the salt into the ice chutes at the same time the chutes are discharging the crushed ice into the hoppers of the refrigerator cars. Each of the chutes 34 comprises opposite side walls 35 and a bottom 36. Mounted in each of the troughs and secured therein is a semi-circular metal trough 37. Rotatably mounted within the trough 37 is a screw conveyor 38. The screw conveyor 38 is secured to a shaft 39 which has its outer end journaled in a bearing bracket, generally indicated by the reference character 40. The inner end of each of the shafts 39 is journaled in an end bearing plate 41 which, in turn, conforms to and is secured to the inner end of each of the troughs 34. The inner end of each of the conveyor troughs 34 is rigidly secured to a supporting bracket 42. This bracket 42 is preferably in the form of a hollow rectangular construction and has arcuate recesses on the opposite sides, as shown at 43, for receiving and securing therein the inner end of the trough 34. This bracket 42 is rigidly secured to a shaft 44. The opposite ends of the shaft 44 are journaled in oppositely disposed bearings 45. The bearings 45 are secured to a base support, generally indicated by the reference character 46. Each of the base supports 46, in turn, is secured to diagonally supported supplemental frame member 47 which has its outer end secured to one of the channel members 20 and its inner end secured to a longitudinally extending supplemental frame member 48. The opposite ends of the supplemental frame member 48 are secured to the opposite members 20 of the main frame. Mounted on the top surface of each of the brackets 42 is an electric motor 49 which, in turn, is

operatively connected by a coupling member 50 to operatively drive a worm, generally indicated by the reference character 51. The worm and worm shaft is supported in suitable bearings on the opposite sides of each of the conveyor troughs 34. The worm 51 is geared to a worm wheel, generally indicated by the reference character 52, which, in turn, is secured to the inner end of each of the shafts 39 of the conveyor.

Each of the electric motors 49 is provided with suitable wiring connections (not shown). These motors are connected to separate and independent time switches, generally indicated by the reference characters 53 and 54, which are mounted adjacent the operator's station 18' of the icing machine so that easy access to the operation and control of the salt supplying attachment may be had from the icing machine. The time switches 53 and 54 are of the conventional construction except that they are calibrated in pounds of salt so that the operator may set the dial of the switch to any predetermined amount of salt and upon each actuation of the push button, the amount of salt previously set will automatically be measured and discharged by the conveyor into the crushed ice chute.

From the above description it will be seen that the inner end of the conveyor trough 34 and its driving motor 49 is pivotally attached through the medium of the shaft 44 to the bearings 45 so that the outer free end of each of the conveyor troughs 34 may be raised or lowered with respect to the ice chutes 18 so as to properly adjust each of these troughs with respect to their respective chutes in the function of delivering salt into these chutes as the crushed ice is being discharged into the hoppers of the refrigerator cars. At the same time, manually controlled means or mechanical or hydraulically operated means may be connected to the outer ends of these troughs for raising them to inoperative position or the position shown in Fig. 3 when it is desirable to raise either one or both of the ice chutes 18. The operation of all of these controls are operable by the operator on the operator's station 18'.

In this connection it will also be noted that time switches 53 and 54 are operatively connected with each of the motors 49 and controlled from the operator's platform on the icing machine, so that a pre-determined or measured amount of salt may be discharged into the crushed ice being discharged so as to satisfy the requirements of the particular perishable goods being iced in the refrigerator cars.

Summarizing the advantages and functions of operation of my improved salt supplying attachment for icing machines, it will be readily seen that I have provided a very simple, compact and efficiently operated device which is not only adapted to be used as an attachment for a variety of icing machines, but will also permit the adjustment of the conveyor troughs in conformity with the requirements and operation of the icing machine and at the same time will supply a pre-determined measured amount of salt according to the requirements and also permit these adjustments and control of the operation from the operator's platform on the icing machine.

While in the above specification I have described one embodiment which my invention may assume in practice, it will, of course, be understood that the same is capable of modification and that modification may be made without departing from the spirit and scope of the invention as expressed in the following claims.

What I claim as my invention and desire to secure by Letters Patent is:

1. The combination with a refrigerator car icing machine having an ice crushing mechanism and laterally projecting chutes for discharging crushed ice into the hoppers of refrigerator cars, of a salt supplying attachment operatively connected to and located rearwardly of said machine including a frame, a salt hopper supported on said frame, oppositely disposed conveyor troughs pivoted to said frame and having their salt receiving ends positioned below the hopper and their outer ends positioned over the opposite chutes, screw conveyors mounted in each of said troughs, and separate motors mounted on each of said troughs and pivoted to said frame and operatively connected to the respective screw conveyors for driving the same.

2. The combination with a refrigerator car icing machine having an ice crushing mechanism and laterally projecting chutes for discharging crushed ice into the hoppers of refrigerator cars, of a salt supplying attachment operatively connected to said machine including a frame, a salt hopper supported on said frame, oppositely and outwardly diverging conveyor troughs pivoted to said frame and having their salt receiving ends positioned below the hopper and their outer ends positioned over the opposite chutes, screw conveyors mounted in each of said troughs, and separate motors mounted on each of said troughs and pivoted to said frame on axes common with the pivot of said troughs, said motors being operatively connected to the respective screw conveyors for driving the same.

3. The combination with a refrigerator car icing machine having an ice crushing mechanism and laterally projecting chutes for discharging

crushed ice into the hoppers of refrigerator cars, of a salt supplying attachment operatively connected to said machine including a frame, a salt hopper supported on said frame, oppositely disposed and outwardly diverging conveyor troughs pivoted to said frame and having their salt receiving ends positioned below the hopper and their outer ends positioned over the opposite chutes, screw conveyors mounted in each of said troughs, and separate motors mounted on each of said troughs and operatively connected to the respective screw conveyors for driving the same.

4. The combination with a refrigerator car icing machine having an ice crushing mechanism, a laterally projecting chute for discharging crushed ice laterally from the crushing mechanism, of a salt supplying trailer attached to and propelled by the icing machine, said trailer including a frame, a salt hopper mounted on said frame, a salt conveyor trough pivoted to said frame at a point below the hopper and having its outer end positioned over said chute, a screw conveyor journaled in said trough, and a motor supported on the pivot of said trough and operatively connected to said screw conveyor for operatively driving the same.

HAROLD O. McLAIN.
